UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

HAND BRAKE FOR RAILWAY CARS.

Application filed April 3, 1924. Serial No. 703,903.

To all whom it may concern:

Be it known that I, JOHN F. O'CONNOR, a citizen of the United States, residing at Chicago, in the county of Cook and State 5 of Illinois, have invented a certain new and useful Improvement in Hand Brakes for Railway Cars, of which the following is a full, clear, concise, and exact description, reference being had to the accompanying 10 drawings, forming a part of this specification.

This invention relates to improvements in hand brakes for railway cars.

In the operation of hand brakes of the 15 vertical staff type for railway cars, difficulty has been experienced heretofore due to the binding of the staff when released. Binding of the staff is frequently caused by the bulging of the end wall of the car or by 20 bending of the staff, with the result that even though the brake is released in the usual manner, the chain will not become fully slack, thereby permitting the brake shoes to remain in contact with the wheels.

25 One object of my invention is to provide an arrangement especially adapted for hand brakes of railway cars, wherein provision is made for positively insuring the full and complete release of the hand brake mechanism, to the end that the brake shoes may be freely disengaged from the wheels to minimize wear therebetween and reduce the tractive effort required of the locomotive.

30 Other objects and advantages of my invention will more clearly appear from the description and claims hereinafter following.

In the drawing forming a part of this 35 specification, Figure 1 is a vertical sectional view taken through the end wall of the car and showing my improvements in connection therewith. Figure 2 is a horizontal sectional view of the structure illustrated in Figure 1 and corresponding to the section line 2-2 thereof. Figure 3 is a plan view of the clutch face of the slidable clutch member. Figure 4 is a fragmentary vertical sectional view of a modified form of device. And Figure 5 is a horizontal section- 40 al view taken substantially on the line 5-5 of Figure 4.

In said drawing, the end wall of the car is indicated at 10, and a housing or bearing bracket designated generally by the reference character A is secured thereto. Said

bracket is provided with a rear wall 11 riveted or otherwise rigidly secured to the car wall 10 by means of rivets 12, said bracket also having a bottom web or wall 13 extending horizontally and provided with a journal bearing 14, an intermediate web or partition 15 extending horizontally, above the web 13, and vertical flanges 16 and 17 connected toward their front end by a rounded portion 18. A cap or cover plate 19 is also employed and is preferably secured to the main portion of the bracket casting A by the bolt 34, hereinafter referred to.

A portion of the usual vertical brake staff 70 is indicated at 20, the same being squared or of other non-circular cross section at the top thereof and on which is rigidly fitted a ratchet wheel B. The ratchet wheel B is provided with an upper and a lower set 75 of ratchet teeth 21 and 22, respectively, the lower and upper ends of the ratchet being provided with journals 23 and 24, respectively, the lower journal rotating in the bearing 14.

Oscillatably mounted on the journal bearing 24 is a carrier or fulcrum member 80 designated generally by the reference character C. Said carrier C has a substantially annular depending flange 24' from which are extended lateral wings 25-25. Pivotally mounted between the wings 25 on a horizontal pivot bolt 26 is an operating handle or lever 27. The handle 27 is provided at the top end thereof with a longitudinally extending socket 28, within which is slidably mounted a pawl 29 normally impelled outwardly by means of a spring 30. The arrangement of the handle and pawl is such that when the handle is elevated to a horizontal position, the pawl is operatively engaged with the teeth 21 of the ratchet wheel B and when the handle is released, it automatically falls to a depending vertical, inoperative position as shown in Figure 1. 90 With this arrangement, it is evident that the staff may be rotated in a winding direction with a step by step movement in the usual manner.

To hold the staff against accidental reverse rotation, I preferably employ the following means: A dog 31 is oscillatably mounted between the webs 13 and 15 so as to coact with the teeth 22 of the ratchet wheel B. This dog has a tooth 32 at its inner end 100

to coact with the ratchet teeth and is provided with a handle or lever extension 33 at its other end whereby the tooth 32 may be manually disengaged from the ratchet wheel. A vertically extending bolt 34 is positioned through the bracket, and a bushing or sleeve 35 is mounted on said bolt, said bushing having its exterior of square or other non-circular cross section and fitting 5 into a cooperating recess in the dog 31, so that the sleeve and dog will rotate or oscillate in unison. The upper portion of the sleeve 35 is provided with an enlarged portion having clutch teeth 36 on its upper face, said enlarged portion resting on the upper surface of the web 15 of the bracket. A clutch member 37 is arranged to slide vertically upon the bolt 34, said member having clutch teeth 38 at its 10 lower end, adapted to coact with the clutch teeth 36 of the sleeve member and is also provided with a non-circular portion 39 at its upper end, the latter portion being slideable vertically but non-rotatable in a cooperating guide 40 formed integral with the bracket as shown.

A spring 41 normally presses the clutch member 37 downwardly and a spring 42 normally presses the tooth 32 of the dog into engagement with the ratchet teeth 22 of the ratchet wheel. A cam 43 is carried by the depending wall 24' of the carrier member so as to project radially therefrom, said cam being engageable with the portion 39 of the 30 clutch member 37 to lift the clutch member 37 from the clutch teeth 36 of the sleeve when the carrier member is oscillated toward its starting position for winding the chain.

40 The operation of the hand brake is as follows: Assuming that the parts are in their operative position shown in Figures 1 and 2, with the clutch teeth 38 riding on the flat faces of the clutch teeth 36, then when the 45 ratchet wheel is advanced in a step by step movement, the tooth 32 being spring-influenced by the spring 42 will permit this step by step movement of the ratchet wheel and hold said ratchet wheel against reverse 50 rotation. When it is desired to release the dog from its holding engagement with the ratchet wheel, the release lever 33 is pulled, thereby disengaging the tooth 32 from the ratchet wheel and oscillating the sleeve 35 55 in unison with the dog, whereupon the spring 41 will cause the clutch 37 to move downwardly so that its clutch teeth 38 mesh with the clutch teeth 36 and hold the dog against reengagement with the teeth of the 60 ratchet wheel B. Consequently, the brake staff, even though it may stick or bind during the latter portion of the release of the 65 brakes, will nevertheless be free to continue its rotation in an unwinding direction when the car gets in motion and jarring of the

brake chain occurs, to permit the brake shoes to become fully disengaged from the wheels and the brake chain to be fully slack.

When the brake is later applied to again wind the chain, the brakeman elevates the 70 handle 27 and pushes or oscillates the same to its extreme starting position, thereby oscillating the fulcrum member or carrier C therewith, to cause the cam member 43 carried thereby to engage the portion 39 of the 75 clutch member 37, lifting the clutch teeth 38 out of mesh with the teeth of the sleeve 35, thereby permitting the spring 42 to exert its influence to press the tooth 32 of the dog into engagement with the teeth 22 of the 80 ratchet wheel B, thus restoring the locking dog and associated parts to their normal operative position. In this connection, it will be understood that the area of contact of the 85 flat portions of the clutch teeth 36 and 38 is of sufficient extent, when the parts are in normal operating position to prevent the clutch teeth 38 from falling into engagement with the teeth 36 while the dog 31 ratchets over the teeth of the ratchet wheel B.

In the form shown in Figures 4 and 5, A' indicates the bracket, B' the ratchet wheel, and C' the fulcrum member or carrier member for the operating handle. The holding dog 131 is pivotally mounted upon 90 the vertical bolt 134 carried by the bracket A', the inner end of the holding dog being provided with a tooth 132 adapted to coact with the teeth of the ratchet wheel B'. The release handle 133 is connected to the holding dog 131 so that when the release handle is pulled, the tooth of the dog will be disengaged from the ratchet teeth. Clutch teeth 136 are provided on the upper face of the 95 hub of the holding dog, said dog being free to rotate upon the bolt 134 as shown. Washers 145 may be interposed between the hub of the dog and the bottom of the bracket, if desired, said washers being mounted upon the bolt 134. A clutch member 137 is non-rotatably but vertically slidably mounted upon the bolt 134, the bracket A' being provided with a guide 140 to prevent rotation of the 100 clutch member 137 but permit the vertical sliding thereof. A spring 141 may be interposed between the top of the bracket and the clutch 137 to yieldingly press the same downwardly, said clutch having clutch teeth 138 on its lower face, adapted to mesh and coact with the cooperating clutch teeth 136 of the dog. In this modification, the spring corresponding to the spring 42 of the previous modification is unnecessary as the shape of the clutch teeth 138 and 136 is such 105 as to exert a camming action and the dog is normally urged into engagement with the teeth of the ratchet wheel B'. The ratchet wheel may be rotated in a step by step movement and as the tooth 132 is moved outwardly by the ratchet wheel B' a distance

sufficient to permit it to reengage behind the next ratchet tooth, the clutch teeth 136 will act as a cam to lift the clutch member 137 upwardly against the pressure of the spring 141 to permit of this step by step movement. When it is desired to release the dog from its holding engagement with the ratchet wheel, the release handle 133 is pulled, thereby camming the clutch member 137 upwardly so that its clutch teeth ride on the top faces of the clutch teeth 136 and frictionally hold the dog against reengagement with the teeth of the ratchet wheel B'.

A lug or projection 144 is carried by the clutch portion 136 of the dog, as shown in Figures 4 and 5 and a portion of the periphery of the carrier member C' is recessed or cut back to form a groove 142, the ends of the cut back portions forming shoulders 146. When the release handle 133 is pulled to release the tooth 132 of the dog from the ratchet wheel B', the projection 144 carried by the dog will remain in the position shown in dotted lines in Figure 5, while the dog is being held in released position. When it is desired to wind the brake staff again, the operating handle is lifted to its operative position and is then swung to one extreme position, causing the carrier member C' to oscillate, during which oscillation the shoulder 146 engages with the projection 144 to oscillate the pawl relatively to the non-rotatable clutch member 137 so that the teeth 136 and 138 are in mesh to permit the step by step movement of the ratchet wheel B'.

I have herein shown and described what I now consider the preferred manner of carrying out the invention but the same is merely illustrative and I contemplate all changes and modifications that come within the scope of the claims appended hereto.

I claim:

1. In a hand brake, the combination with a rotatable ratchet wheel; of means for rotating said wheel in a chain-winding direction; a release lever; a locking dog integral with said lever and cooperable with said ratchet wheel to hold the same against rotation in a reverse direction and adapted to be actuated by said lever to an inoperative position; and spring-influenced means automatically operable to hold said dog in its inoperative position out of engagement with said ratchet wheel, said means being arranged to have certain relative movement to permit normal ratcheting of said dog without locking the same.

2. In a hand brake, the combination with a vertical staff and a ratchet wheel rotatable therewith; of means for rotating said staff in a winding direction; a release lever; a locking dog integral with said lever and cooperable with said ratchet wheel to hold the same against rotation in a reverse direction

and adapted to be actuated to an inoperative position by said release lever; and clutch means non-rotatable with said dog and automatically coacting therewith to hold the latter in its inoperative position out of engagement with said ratchet wheel when the release lever is actuated, said clutch means being arranged to have relative movement therebetween to permit normal ratcheting of said dog without actuation of said holding means.

3. In a hand brake, the combination with a rotatable ratchet wheel; of means for rotating said staff in a step by step movement; a release lever; a locking dog operably connected to said lever to move in unison therewith and hold the ratchet wheel against rotation in a reverse direction; a clutch member movable in unison with said dog and provided with clutch teeth; a clutch member non-rotatably but vertically movable into engagement with said first-mentioned clutch teeth to hold said dog in its inoperative position out of engagement with said ratchet wheel, the teeth of said clutch members being arranged to have certain relative movement to permit normal ratcheting of said dog; and means for automatically actuating said clutch member.

4. In a hand brake, the combination with a rotatable ratchet wheel; of means for rotating said staff; a release lever; a locking dog cooperable with said ratchet wheel to hold the same against rotation in a reverse direction and adapted to be actuated by said lever to an inoperative position; a clutch element associated with said dog and actuated thereby; a spring-influenced clutch member non-rotatable but vertically movable into bearing engagement with said clutch element and arranged to permit relative movement between said clutch member and clutch element to permit normal ratcheting of said dog, said clutch member and element being operable to hold said dog in its inoperative position out of engagement with said ratchet wheel when the release lever is actuated; and means carried by said rotating means to release the dog holding means.

5. In a hand brake, the combination with a ratchet wheel; of means for rotating said staff in a step by step movement in a chain-winding direction; a fulcrum member for said means; a release lever; a locking dog cooperable with said ratchet wheel to hold the same against rotation in a reverse direction and adapted to be actuated by said release lever in unison therewith to an inoperative position; a clutch part carried by said dog; a spring-influenced clutch member arranged above said clutch part and non-rotatable but vertically movable to coact therewith to hold the dog in its inoperative position out of engagement with said ratchet wheel, said clutch member and clutch part

being capable of limited relative movement to permit ratcheting of said dog without locking the same in inoperative position; and means on said carrier to engage said clutch member to release said dog so that it may reengage said ratchet teeth.

6. In a hand brake for railway cars, the combination with a rotatable member adapted to effect tightening of the brake chain and rotated in one direction, said member having a ratchet wheel rotatable in unison therewith; of means for effecting step by step rotation of said member in a chain winding direction; a dog co-operable with said ratchet wheel and movable toward and from the axis of said ratchet wheel; a release element for moving said dog to an in-

operative position; a clutch element immovably associated with said dog and partaking of its movements; a second clutch element arranged to co-operate with said first named clutch element, said second clutch element being movable in a direction toward and from the first named clutch element and normally influenced toward the first named clutch element, co-operating to prevent return of the dog to operative relation with respect to the ratchet wheel when said dog has been manually actuated to full release position.

In witness that I claim the foregoing I have hereunto subscribed my name this 1st day of April 1924.

JOHN F. O'CONNOR.
